AMERICAN MANGANESE STEEL COMPANY, OF AUGUSTA, MAINE, A CORPORATION
OF MAINE.

RAILROAD-CROSSING.

1,127,495.

Specification of Letters Patent.

Patented Feb. 9, 1915.

Application filed December 2, 1914. Serial No. 875,067

To all whom it may concern:

Be it known that I, WESLEY G. NICHOLS, a citizen of the United States, and a resident of Chicago Heights, in the county of Cook and State of Illinois, have made and invented certain new and useful Improvements in Railroad-Crossings, of which the following is a specification.

This invention relates to an improvement in railroad crossings and more particularly to the construction of intersections constituting the same. By reason of the inherent characteristics of toughness and hardness of manganese steel, and the consequent long life and superior wearing qualities of the same, it is desirable to use such metal in the construction thereof, and to make the intersection of as small a number of parts as possible, due to the fact that it is extremely difficult to drill or machine the same. I have experimented to a considerable extent in casting these intersections in one piece, but have found that due to the peculiar action of the intersections in service, the fatigue point occurs at the center of the casting, where the rails intersect and where the steel is most rigid, and at these points most frequently occur the breaks and fractures, the same taking place before the balance of the casting is to any appreciable extent impaired or injured. To overcome this defect the thickness of the casting was materially increased at the center, which in a measure obviated difficulties, but without totally eliminating the same. In the reinforcing of the center of the castings, a large amount of metal was used, which, of course, adds materially to the cost, and at the same time imparts to the intersection a rigidity far greater than that which has proved to be the best practice. Furthermore it is unadvisable to reinforce the center of the intersection to such extent as to give a sufficient amount of metal to add the necessary strength to prevent its breaking or cracking in service, because of the formation of what is usually termed an "unequivalent section," by which is meant, a section of varying thickness, for instance, a section tapering from approximately four inches at its center to a one inch end, which occurs approximately midway between the two adjacent elements of intersections of the complete crossing. The difficulty encountered in the casting of such a section lies in the compensa-

tion which must be made for shrinkage, and almost impossible task of uniformly densifying all portions of the casting when feeding from one point, without using an excessive amount of metal. The foregoing is particularly characteristic of casting of manganese steel which has a shrinkage nearly double that of other forms of steel.

In designing my improved crossing I have aimed to avoid the above mentioned objections, and with these and other objects in view, the invention consists in certain novel features of construction of parts as will be hereinafter described in claims, it being noted that changes in the precise embodiment of the invention can be made within the scope of what is claimed, without departing from the spirit of the invention.

In the drawings accompanying this specification and forming a part thereof, the preferred embodiment of my invention is illustrated.

Figure 1 is a view in plan of two connected intersections embodying my invention, and constituting one-half of a crossing. Fig. 2 is an enlarged plan view of an intersection. Fig. 3 is a view in vertical section taken on the line 3—3 of Fig. 2. Fig. 4 is a similar view taken on the line 4—4. Fig. 5 is a view in top plan of the lower or supporting member of an intersection. Fig. 6 is a view in perspective taken on the line 6—6 of Fig. 5. Fig. 7 is a view in top plan of a somewhat modified form of intersection. Figs. 8 and 9 are sectional views taken on the lines 8 and 9 respectively of Fig. 7. Fig. 10 is a view in perspective of the supporting member of the modified form of intersection.

Referring to the drawings in which similar reference numerals designate corresponding parts throughout the several views, the crossing is made up of four intersections, identical throughout, in view of which, only one will be treated in detail. Each intersection includes a supporting base 15 from which project the crossed filler bars 16, the same rising upwardly from the plate and formed or cast integral therewith. A cast member 18, rests upon the base plate 105 and constitutes crossed and connected rails, 19, these rails being provided with the longitudinally extending and crossed channels 20, dividing the rails into the wearing portions 21, and guards 22. The central por-

tions of the channels extend entirely through the cross-rail member 18, to thus define open slots 23, into which the filler bars 16 extend. It is to be noted in this connection, that one of the objects of the invention is to provide a crossing embodying a certain amount of resiliency and with this in view the open slots 23, are formed a little longer than the filler bars which are contained therein, defining open spaces 24 between the ends of the slots and filler bars, allowing for the flexing or bending of the parts constituting the intersection.

The main wearing portions of the crossed rails are cored as illustrated at 25 in Fig. 4, producing a casting of nearly uniform or equivalent section throughout, the same being of such prime importance in manganese steel castings. In order to brace and strengthen the cross-rail member or casting, the elbows at 26 are utilized, the same being positioned against the webs of the rails and disposed intermediate the heads and flanges thereof. The filler bars and cross-rail members are provided with suitable apertures 28 and 29 through which the bolts 30 extend, thus providing for the efficient securing of the base and cross-rail member. The apertures within the filler bars are of a sufficient size to allow a slight relative flexing of the two above mentioned members without danger of shearing or fracturing the holding bolts. In order to more positively secure the cross-rail member to the supporting plate, the clamps 31 are employed, and, as illustrated in Fig. 4, are securely bolted to the base plate and engage the flanges of the cross-rail member. The greatest wear upon an intersection occurs at the meeting corners of the crossed rails and causes the discarding of the more expensive part of the intersection, that is, the cross-rail member. In order to obviate this, the adjacent corners of the cross-rail member are cut away as indicated by the lines 32, and suitable inserts 33 of the exact size and shape of the removed portions are formed integral with the base plate 15 and filler bars 16. After the adjacent corners 33 of the crossed rails become worn, the supporting base is discarded and a new base with inserts is substituted therefor, thus materially increasing the life, of the intersection and reducing its cost of upkeep.

The formation of filler bars or ribs 16 upon the base plate materially strengthens the same, but does not impair the resiliency of the assembled intersection. The formation of the filler bars upon the base plate, and the removal of a corresponding amount of metal from the center of the cross-rail member, provide for the casting of manganese steel under most favorable conditions, that is, in equivalent sections. The intersections are joined by the rail lengths

34 preferably cast integral therewith as disclosed in Fig. 1. Two extremities of the rails of each intersection are prolonged as at 35 and form attaching ends to which the extremities of rails may be secured. The somewhat modified form of intersection disclosed in Figs. 7 to 10 inclusive is modified to the effect, only, that the corner inserts 33 are omitted.

Having thus fully described my invention what I claim is:

1. A crossing intersection comprising a supporting member including a base plate with crossed upstanding filler bars, and a top member including crossed runways, said runways adapted to receive said filler bars therein.

2. A crossing intersection comprising a base plate with upstanding crossed filler bars, and a detachable member resting upon said plate and including runways.

3. A crossing intersection comprising a base plate with crossed filler bars, and a cross-rail member provided with slots extending entirely therethrough and adapted to receive said filler bars.

4. A crossing intersection comprising a base plate with crossed filler bars, and a cross-rail member provided with slots extending entirely therethrough adapted to receive said filler bars, and holding means extending through said filler bars and cross-rail member.

5. A cast manganese steel crossing intersection comprising a base member including upstanding crossed ribs, a cross-rail member provided with slots receiving said ribs therein.

6. A cast manganese steel crossing intersection comprising a base member including upstanding crossed ribs, a cross-rail member provided with slots receiving said ribs therein, said slots relatively longer than the contained ribs.

7. A cast manganese steel crossing intersection comprising a base member including upstanding crossed ribs, a cross-rail member provided with slots receiving said ribs therein, said slots relatively longer than the contained ribs, and holding means extending through said filler bars and cross-rail member.

8. A crossing intersection comprising a supporting member including filler bars, a cross-rail member provided with longitudinal grooves, the said grooves adjacent the meeting portions of said rails extending entirely through said cross-rail member and adapted to receive said filler bars therein.

9. A crossing intersection comprising a supporting member including filler bars, a cross-rail member provided with longitudinal grooves, said grooves adjacent the meeting portions of said rails extending entirely through said cross-rail member and adapt-

ed to receive said filler bars therein, the central portions of said grooves relatively longer than the said filler bars.

10. A crossing intersection comprising a supporting member including upstanding ribs, a cross-rail member provided with slots adapted to receive said ribs therein, said supporting member provided with upstanding corner inserts projecting within re-

10 cesses.

11. A crossing intersection comprising a supporting member, a cross-rail member bolted thereto, said supporting member including upstanding corner inserts extending 15 within openings provided therefor in adjacent corners of said cross-rail member.

12. A supporting member for a built up crossing intersection comprising a base plate

with upstanding crossed integral filler bars, the center of said filler bars adapted to correspond to the center of the intersection member, which said base plate is adapted to support.

13. A crossing intersection comprising a base plate provided with integral filler bars, 25 and a rail member formed of a single casting and secured to said base plate and slotted to receive said filler bars.

Signed at Chicago Heights, in the county of Cook and State of Illinois, this 24th day 30 of November, A. D. 1914.
